ALFRED E. STAFFORD, OF HOPEDALE, MASSACHUSETTS, ASSIGNOR TO
DRAPER COMPANY, OF HOPEDALE, MASSACHUSETTS, A CORPORA-
TION OF MAINE.

FILLING-REPLENISHING LOOM.

No. 805,497.

Specification of Letters Patent.

Patented Nov. 28, 1905.

Application filed May 29, 1905. Serial No. 262,807.

To all whom it may concern:

Be it known that I, ALFRED E. STAFFORD, a citizen of the United States, residing at Hopedale, in the county of Worcester and State of Massachusetts, have invented an Improvement in Automatic Filling - Replenishing Looms, of which the following description, in connection with the accompanying drawings, is a specification, like characters on the drawings representing like parts.

This invention relates to looms provided with means to replenish automatically the running shuttle with a fresh supply of filling, as in the Northrop type of loom, wherein the fresh filling-carriers are held in reserve in a feeder or hopper at one side of the loom, filling replenishment being effected when the shuttle is boxed at the adjacent end of the lay, as in United States Patent to Northrop, No. 529,940, and others of later date. If for any reason the replenishing mechanism is operated when the shuttle is in the opposite box, the transferred filling-carrier is deposited in the empty shuttle-box, whence it may pass without causing any damage, or considerable damage may be caused by interference with adjacent parts of the loom mechanism or with the incoming shuttle on the next pick. Entirely irrespective of the tendency to cause damage it will be manifest that such operation of the replenishing mechanism is wholly superfluous and that a full filling-carrier has been withdrawn from the feeder unnecessarily and diminishing the reserve supply of filling therein.

My present invention has for its object the production of novel and exceedingly simple means to prevent the operation of the replenishing mechanism when the shuttle is in the wrong shuttle-box, and it is particularly adapted to filling - replenishing looms equipped with two filling - detecting instrumentalities. In such looms means were formerly provided for causing a change in the operation of the take-up upon detection of filling failure at either side of the loom and to effect the operation of the replenishing mechanism primarily through the detecting instrumentalities at the non-replenishing side of the loom. This arrangement required certain important adjustments of parts, lost motion, or some variation in the stroke of the two weft-hammers,

and in the latter case the two actuating-cams for the weft - hammers were different. In United States Patent No. 759,854, granted May 17, 1904, to Benson a construction is shown whereby lost motion is obviated and the use of like cams and coöperating parts for both of the filling-detectors made possible, greatly simplifying the construction and making the operation more positive and direct; but such construction necessitated the provision of means to prevent the operation of the replenishing mechanism when the shuttle was lodged in the wrong shuttle-box, and accordingly the bunter on the lay adapted to engage a member or dog of the controlling means for the replenishing mechanism was made movable with relation to the lay. The dog was moved into its operative position by or through detection of filling failure by either detector; but if the shuttle was in the wrong box the bunter on the lay was moved into inoperative position, so that it could not cooperate with the dog, and no operation of the replenishing mechanism took place until the shuttle was in the replenishing shuttle-box.

In accordance with my invention I secure the same result, but in a different and simpler manner, as I prevent the operative positioning of the member or dog referred to if the shuttle is not in the replenishing shuttle-box. Herein this is effected by the attachment of a detent to the weft-hammer at the replenishing side of the loom to coöperate with the shuttle-feeler, which latter tends to move rearwardly upon detection of filling failure at either side of the loom. The weft-hammer at the replenishing side is so positioned, however, at the instant the shuttle-feeler is tending to move rearwardly, the shuttle then being in the non-replenishing box, that the detent engages the shuttle-feeler and prevents its operative rearward movement. The feeler in turn controls the operative positioning of the dog, as the latter can only attain its operative position when the shuttle-feeler moves into its own operative position. Consequently as the detent arrests the shuttle-feeler the latter prevents the dog from becoming operative and replenishment of filling cannot take place. The control of the dog, and hence of the action of the replenishing mechanism, by or through a shuttle-feeler is not of my inven-

tion, as the same is shown in numerous patterns—such, for instance, as No. 628,228, dated July 4, 1899.

The novel features of my invention will be 5 fully described in the subjoined specification and particularly pointed out in the following claims.

Figure 1 is a top plan view, centrally broken out, of a sufficient portion of an automatic 10 filling-replenishing loom to be understood equipped with double filling-detecting instrumentalities and having one form of my present invention applied thereto, the weft-hammer at the right-hand side being shown in 15 position to prevent filling replenishment even if called for by detection of filling failure. Fig. 2 is a transverse sectional detail on the line 2 2, Fig. 1, looking toward the right, the parts being in a position corresponding to 20 that shown in Fig. 1; and Fig. 3 is a view similar to Fig. 2, but showing the parts in position to effect filling replenishment on the beat-up of the lay, the shuttle being in the proper shuttle-box.

25 The lay A³, having shuttle-boxes B B^X at opposite ends, the filling-replenishing mechanism comprising a feeder F and a transfer 30 rer f' to remove the filling carriers or bobbins b one by one from the feeder to the shuttle S, the controlling rod or rock-shaft d', extending across the loom and having rigidly- 35 attached upturned arms d⁵ d¹⁰ fast thereon and coöperating, respectively, with the outer ends of the slides f^X g^X, on which are mounted the filling detectors or forks f g, one at each side of the loom, and the vibrators or 40 weft-hammers M N, arranged to coöperate with the fork-tails when upon absence of filling either of the forks is not tilted to move 45 the corresponding slide outward, and thereby turn the rock-shaft d' in the direction of arrow 200, may be and are all substantially as in Patent No. 759,854, hereinbefore referred to, the vibrators or weft-hammers being given the same stroke by like and interchangeable 50 cams, but moving in opposite directions.

As the hammers have the same stroke, whichever fork by detection of filling failure causes the rock-shaft d' to be turned will cause 55 it to turn through the same angle, and such angular movement can be readily arranged to change the operation of any suitable take-up instrumentality—as, for instance, to arrest it—by means of an arm d¹², (see Fig. 1,) fast on the rock-shaft and adapted to govern 60 the operation of an instrumentality such as shown in United States Patent No. 727,014.

Referring to Fig. 2, the dog m¹⁵, operatively connected with the transferrer in well-known manner, is normally held in the position therein shown by connections between the dog and the controlling rock-shaft d'. Said connections, as herein shown, include a yoke y^X y², pivoted on the loom-frame at y⁶⁵ and having a lug y', on which the arm d^X is

held by the spring d³, said arm being fast on the controlling rock-shaft, the branch y^X constituting a shuttle-feeler, while the branch y² rests against a lateral lug m¹⁴ on the dog. The parts are arranged to operate in usual manner, rocking of the controlling rock-shaft d' in the direction of arrow 200 lifting the arm d^X and permitting the dog m¹⁵ to move into operative position to be engaged by the bunter C² on the lay if the shuttle is properly boxed, 70 all substantially as in Patent No. 628,228, hereinbefore referred to. If the shuttle projects part way out of the box B^X, the shuttle-feeler y^X cannot complete its movement into operative position, and the branch y² then 75 prevents the operative positioning of the dog m¹⁵.

In accordance with my present invention I have secured to the weft-hammer N a detent, shown as a rigid laterally-extended arm or 80 rod 80, (best seen in Fig. 1,) long enough to pass behind the shuttle-feeler or some part thereof, such as the lateral lug 81, as herein shown, and across the path of movement of such lug and so arranged that when the weft-hammer is back the feeler can move rearward into position to feel for the shuttle. When the weft-hammer is forward or moving forward, however, the detent will engage the lug 81 on the shuttle-feeler and prevent it 85 from moving into operative position even should the rock-shaft d' have been turned to permit it, and consequently the dog m¹⁵ will be prevented from moving into its operative position, and no operation of the replenishing 90 mechanism will take place.

From the foregoing description, in connection with the drawings, the operation will be readily understood, for if filling fails as the shuttle is moving to the box B, Fig. 1, the 105 detector f will usually detect such failure, and the shaft d' will be turned to permit the dog m¹⁵ to become set or operatively positioned on the next pick, as the hammer N will be moving back, and on such next pick when 110 the shuttle enters the box B^X the bunter C² will engage the dog and effect filling replenishment, supposing the shuttle is properly positioned.

Should the filling fail when the shuttle is 115 moving to the box B^X, such failure will be detected by the fork g, its slide will be moved forward to rock the rock-shaft d', as before, and the dog m¹⁵ will tend to become operatively positioned on the next pick; but on 120 that next pick the shuttle will have been thrown from the box B^X to box B—the non-replenishing box. The weft-hammer N will, however, be so far forward at that time that it will act through the detent 80 to arrest the 125 rearward movement of the shuttle-feeler y^X as the lay beats up. This shuttle-feeler in turn holds back the dog, so that it cannot complete its movement to operative position, and hence no actuation of the replenishing 130

mechanism can take place when the shuttle-box B^x is empty and will not take place until the fork f has detected filling failure.

The change in the operation of the take-up 5 is effected each time the rock-shaft d' is turned, so that a thin place will not be made in the cloth. Thus the position of the weft-hammer at the replenishing side of the loom determines whether or not actuation of the replen- 10 ishing mechanism can take place when called for by angular movement of the controlling rock-shaft d' , due to detection of filling failure by either detecting instrumentality. If said weft-hammer is back at the time the dog 15 and bunter would coöperate, filling replenishment can be accomplished, because the shuttle must then be in the proper shuttle-box; but if the said weft-hammer is forward or moving forward coöperation of the dog and bunter is 20 prevented, because the replenishing shuttle-box must then be empty and filling replenishment is prevented.

My invention is not restricted to the precise construction and arrangement herein shown 25 and described, as the same may be varied in different particulars by those skilled in the art without departing from the spirit and scope of my invention, one particular embodiment whereof is herein shown and described.

Having described my invention, what I 30 claim as new, and desire to secure by Letters Patent, is—

1. In a loom, filling-replenishing mechanism at one side thereof, a filling-detecting instrumentality at each side of the loom, means to control the time of operation of said mechanism, including a member tending to be operatively positioned when filling failure is detected by either instrumentality, and means 35 operative independently of the shuttle to prevent such operative positioning of said member when the shuttle is at the non-replenishing side of the loom.

2. In a loom, filling-replenishing mechanism 40 at one side thereof, a filling-detecting instrumentality at each side of the loom, means to control the time of operation of said mechanism, including a member tending to be operatively positioned when filling failure is detected by either instrumentality, and means 45 governed by the detecting instrumentality at the replenishing side of the loom to prevent such operative positioning of said member when the shuttle is at the opposite side of the loom.

3. In a loom, filling-replenishing mechanism 50 at one side thereof, a filling-detector and its coöperating vibrator at each side of the loom, means to control the time of operation of said mechanism, including a member tending to move automatically into operative position upon detection of filling failure by either detector, and means governed by one of said 55 vibrators to prevent such operative position- 60 ing of said member unless the shuttle is in

the shuttle-box at the replenishing side of the loom.

4. In a loom, a lay provided with a bunter and having a shuttle-box at each end, filling-replenishing mechanism at one side of the 70 loom, a filling-detecting instrumentality at each side of the loom, means to control the time of operation of said mechanism, including a member tending to move automatically into the path of the bunter when filling failure is detected by either detecting instrumentality, and means governed by or through one of said instrumentalities to prevent the movement of said member into the bunter-path 75 when the replenishing shuttle-box is empty. 80

5. In a loom provided with filling-replenishing mechanism, a lay, means to control the time of operation of said mechanism, including a member on the lay and a member movable into position to coöperate therewith, two 85 filling-detectors, means tending to effect co-operation of the said movable member and the member on the lay by or through detection of filling failure by either detector, and a device operative independently of the shuttle 90 and the filling therein to counteract such tendency and thereby prevent the operation of the replenishing mechanism if the shuttle is not at the replenishing side of the loom.

6. In a loom provided with filling-replenishing mechanism, a lay provided with a shuttle-box at each end thereof, means to control the time of operation of said mechanism, two filling-detectors, connections between said controlling means and the detectors tending 100 to effect the actuation of the replenishing mechanism by or through detection of filling failure by either detector, and a device operative independently of the shuttle and the filling therein to counteract such tendency 105 and thereby prevent filling replenishment when the shuttle is in the non-replenishing shuttle-box.

7. In a loom provided with filling-replenishing mechanism at one side thereof, means to 110 control the time of operation of said mechanism, including a normally-inoperative member, two filling-detecting instrumentalities operating on alternate picks and both adapted to permit movement of said member into operative position upon detection of filling failure, and means governed by one of said instrumentalities to prevent such operative positioning of said member when the shuttle is 115 at the non-replenishing side of the loom. 120

8. In a loom, in combination, filling-replenishing mechanism, filling-detecting devices at opposite sides of the loom, a rod or rock-shaft extending across the loom and having in connection therewith means to effect the actuation of the filling-replenishing mechanism, operative connections between said rock-shaft and both detecting devices whereby the rock-shaft is operated when either device detects 125 filling failure, and means governed by one of 130

said detecting devices to prevent the operation of said actuating means after operation of the rock-shaft unless the shuttle is at the replenishing side of the loom.

5 9. In a loom, a lay provided with shuttle-boxes, two filling-detecting devices located at opposite sides of the loom and adapted to change the operation of a take-up instrumentality upon detection of filling failure, filling-
10 replenishing mechanism, means to control the time of its operation, including a member tending to move automatically into active position upon detecting action of either detecting device, and means governed by or through
15 one of said detecting devices to prevent the automatic movement of said member into active position if the shuttle is not in the replenishing shuttle-box.

10. In a loom, a lay provided with shuttle-
20 boxes and a bunter, two filling-detecting instrumentalities located at opposite sides of the loom and adapted to change the operation of a take-up instrumentality upon detection of filling failure, filling-replenishing mech-
25 anism, means to control the time of its opera-
tion, including a dog tending to move auto-
matically into position to coöperate with the bunter upon detecting action of either of said detecting instrumentalities, and means gov-
30 erned directly and positively by one of said instrumentalities to prevent the automatic movement of the dog into operative position if the shuttle is not in the replenishing shuttle-box.

35 11. In a loom, in combination, filling-replenishing mechanism, a lay having a bunter and two shuttle-boxes thereon, two filling-detec-

tors located at opposite sides of the loom, a weft-hammer to coöperate with each upon de-
tection of filling failure thereby, means to 40 control the time of operation of said mech-
anism, including a member adapted to move au-
tomatically into position to coöperate with the bunter upon detection of filling failure by either detector, and a detent on one of the weft-
45 hammers to prevent such operative position-
ing of the said member if the replenishing shuttle-box is empty.

12. In a loom, in combination, filling-replen-
ishing mechanism, a lay having a bunter and 50 two shuttle-boxes thereon, a filling-detector and a coöperating weft-hammer at each side of the loom, means to control the time of opera-
tion of said mechanism, including a mem-
ber movable automatically into operative po-
sition with relation to the bunter upon detec-
tion of filling failure by either detector, a shut-
tle-feeler to prevent such positioning of said member when the shuttle is improperly posi-
tioned in the replenishing shuttle-box, and a 60 detent on the weft-hammer adjacent the shut-
tle-feeler and adapted to coöperate therewith at times, to prevent movement thereof into shuttle-feeling position, and thereby to pre-
vent operative positioning of the said mem-
ber controlled thereby, when the shuttle is 65 out of the replenishing shuttle-box.

In testimony whereof I have signed my name to this specification in the presence of two sub-
scribing witnesses.

ALFRED E. STAFFORD.
